(57) **CLAIM**

I claim the ornamental design for a “laser light projector,” as shown.

DESCRIPTION

FIG. 1 is a perspective view of the laser light projector; and, FIG. 2 is a left side view of the laser light projector of FIG. 1;

FIG. 3 is a right side view of the laser light projector of FIG. 1;

FIG. 4 is a front side view of the laser light projector of FIG. 1;

FIG. 5 is a back side view of the laser light projector of FIG. 1;

FIG. 6 is a top view of the laser light projector of FIG. 1; FIG. 7 is a bottom view of the laser light projector of FIG. 1; and,

FIG. 8 is an environmental view of the laser light projector of FIG. 1.

The broken lines in the views represent portions of the projector which form no part of the claimed design.
